UNITED STATES PATENT OFFICE

CHARLES T. WESTLAKE, DECEASED, LATE OF ST. LOUIS, MISSOURI, BY LILIAN A. WESTLAKE, ADMINISTRATRIX, OF ST. LOUIS, MISSOURI, ASSIGNOR, BY MESNE ASSIGNMENTS, TO GENERAL STEEL CASTINGS CORPORATION, OF GRANITE CITY, ILLINOIS, A CORPORATION OF DELAWARE.

ROCKER BEARING

Original application filed April 4, 1925, Serial No. 20,832. Divided and this application filed February 18, 1926. Serial No. 89,071.

This invention relates to new and useful improvements in railway rolling stock and more particularly to the bearings which transfer a portion of the load from the vehicle underframe to the truck such as is shown and described in an application filed April 4, 1925, bearing Serial Number 20,832, of which this is a division.

The principal object of the invention is to provide a self-centering or aligning bearing that will, by virtue of its structure, act to align the vehicle body and the truck wheels.

Another object is to provide means for maintaining proper relationship of the parts in all possible working positions.

A still further object is to provide means for lubricating certain surfaces where there is frictional contact.

With the foregoing and other objects in view, the invention consists in certain novel features of construction and arrangement of parts, hereinafter more fully described and claimed, and illustrated in the accompanying drawings, in which—

Figure 1 is partly a side elevation and partly a sectional view along the line 1—1 of Figure 3.

Figure 2 is partly an end elevation and partly a sectional view through line 2—2 of Figure 3.

Figure 3 is a top plan view of the rocker member.

Figure 4 is a side elevation of the cradle portion of a locomotive and a trailer truck illustrating an adaptation of the rocker bearing.

Figure 5 is a top plan view of the cradle portion of a locomotive and trailer truck shown in Figure 4.

The numeral 1 in the drawings indicates the frame of a railway truck in which are drilled dowel holes 2. A rocker seat bearing base 3 is provided with dowels 4 adapted to fit into the dowel holes 2. The top surface 5 of the rocker seat bearing is slightly concave transversely of the truck frame and is provided with upstanding sides 6. The rocker seat 7 rests on the rocker seat bearing 3 and is provided with an undersurface 50 slightly convex to correspond to the top sur-

face 5 of the rocker seat bearing. Depending lips 8 extend over the ends of the rocker seat bearing to prevent displacement.

Two parallel grooves or sockets 9 are equidistantly spaced from the center of the top surface of the rocker seat. A rocker member 10 is provided on the bottom with two spaced cylindrical members 11 adapted to seat in the parallel grooves 9. The top surface of this rocker comprises two curved portions, both being arcs struck from equal radii but from different centers, and openings 12 are provided in the top surface of the rocker on either side of the center. The rocker 10 supports the bearing plate 13, the under surface of which comprises two parts 15 and 16, each of which slopes upwardly toward the center. Downwardly depending lugs 14 are spaced from the center of bearing plate 13. These lugs are adapted to pass through the openings 12 in the rocker and help to maintain the proper relation between the parts.

In all possible operating positions of the rocker assembly, at least one of the lugs extends into its opening 12 in the rocker. This insures the proper arrangement of the parts and since my rocker assemblies are customarily used in pairs, it maintains each individual rocker in proper position relative to its companion.

It is preferable in the adaptation of the centering means to arrange the rocker and its correlated parts so that the plane of the rocker movement is tangent to an arc struck from the pivot point of the truck. However, it is feasible to make the entire bearing conform to the arc of the curve struck from the pivot point, in which case the parts, instead of being formed in straight pieces as shown in the drawings, would be curved. It would also be possible to make each half of the bearing assembly tangent to this arc.

The bearing plate 13 acts as a load supporting member and is carried by the vehicle underframe to transfer a portion of the weight of the vehicle to the truck through the medium of the rocker bearing and while in the present disclosure plate 13

is a separate piece, my invention contemplates its incorporation as an integral part of the underframe.

A pocket 17 is formed in the lower portion of the body of rocker 10 to receive and store a quantity of lubricant. Waste or some similar material is used to aid in retaining this lubricant. Openings 18 lead from pockets 17 to the lower surfaces of the cylindrical members 11 so that any tilting movement of the rocker 10 distributes lubricant in each of the sockets 9.

Figures 4 and 5 illustrate the method of adapting the rocker bearing to the trailer truck of a locomotive. 19 is the cradle portion of the locomotive frame to the rear of the driving wheels 20. The customary side bearing arms 21 and foot plate 22 are carried by cradle 19. Trailer truck 23 is pivotally connected to the locomotive frame at the point 24 at the forward end of the cradle and consists of two converging side frames 25 and a transverse member 26. The transverse member 26 of the trailer truck lies under the side bearing arms 21 of cradle 19 and is provided with a depressed portion 27 at either extremity to form a suitable seat 28 for my rocker bearing. The bearing plates 13 in this adaptation are connected to the undersides of the side bearing arms 21 or they may be cast integrally therewith as heretofore mentioned. The rockers 10 are tangent to an arc struck from a pivot point 24 of the trailer truck.

When this installation is properly made, the rocker bearings in each corner of the trailer truck will act to yieldingly maintain the proper alignment of the trailer truck wheels 28 with the driving wheels 20 of the locomotive by utilizing the weight supported by the locomotive in the manner hereinafter explained.

In the operation of the improved rocker bearing, when the vehicle is traveling along a straight track, the normal position is that shown in full lines in Figure 1 with the peak of the rocker 10 resting in the angle formed by the inclined undersurfaces 15 and 16 of the bearing plate. Both cylindrical members 11 of the rocker rest in their sockets 9. Upon entering a curve, the truck frame and rocker assembly move in relation to the bearing plate which is carried by the vehicle underframe. The rocker 10 is tilted so that it is supported by only one of the off-center cylindrical members 11, as shown by the dotted lines in Figure 1.

Lugs 14 prevent bearing 13 from sliding over the rocker by their engagement with openings 12, and as the point of contact between the rocker and the bearing plate is changed, the bearing plate is lifted due to its inclined undersurface. Upon regaining a straight track, the action of the rocker is

to realign the truck and the vehicle frame since by gravity the rocker 10 will seek the highest point of the bearing plate 13. The rocker is so positioned that, when installed, it rests upon both cylindrical members 11 when the apex of its surface is in the angle formed by the surfaces 15 and 16 of the bearing plate. It is also installed in such a manner that its normal position as shown by the full lines in Figure 1 is attained when the wheels of the truck are aligned with the body of the vehicle. This is the correct relation between the vehicle underframe and truck when the vehicle is traveling on a straight track.

To allow for irregularities in the castings and to insure proper cooperation when more than one rocker assembly is used, I provide side shims 29 under the rocker seat bearing base whereby the height of the rocker 12 may be adjusted. To maintain proper contact between the rocker, which is carried by the truck, and the bearing plate, which is carried by the underframe, is the function of the concavo-convex bearing of the rocker seat bearing and the rocker seat. This construction leaves the rocker seat free to tilt in relation to the rocker seat bearing longitudinally of the truck or transversely of the plane of the rocker movement. Such transverse rocker seat movement provides for the slight change in angularity between the horizontal bearing surface on truck and vertical alignment of rocker due to the increase in the distance between truck and cradle at rockers when truck swings laterally. The transverse angularity between rocker and cradle remains the same. The upstanding flanges of the rocker seat bearing limit the movement of the rocker and flanges 6 and depending lips 8 of the rocker seat prevent lateral displacement of the seat and seat bearing.

It is to be understood that minor changes in the size, form and construction of the various parts of the invention may be made and substituted for those herein shown and described, without departing from the spirit of my invention as set forth in the appended claims.

What is claimed is:

1. A rocker bearing including a rocker having curved segmental faces with openings therein meeting in a peak and off-center cylindrical feet on said rocker on which said rocker is adapted to pivot, a load supporting member, and lugs on said load supporting member, one or more of which engages said openings in all operating positions of said rocker.

2. In a rocker bearing device, a seat adapted to pivot in one direction, and a rocker pivoted on said seat and adapted to rotate about the axis of its pivot in a transverse direction.

3. In a rocker bearing device, a seat, a rocker pivoted about a predetermined axis on said seat, said rocker and seat being adapted to pivot as a unit transversely of the plane of movement of said rocker on said seat. 5
4. In a device of the class described, a base, a seat pivoted on said base in one plane, and a load supporting rocker pivoted on said seat to rotate in a transverse plane about a predetermined axis on said seat. 10
5. In the device of the class described, a base having a concave upwardly facing bearing, a seat having a complementary downwardly facing bearing resting in said base bearing and also having an upwardly facing concave bearing, and a rocker having a complementary downwardly facing bearing pivotally seated in said latter mentioned seat bearing. 15
6. In a device of the class described, a base having a concave upwardly facing bearing, a seat having a complementary downwardly facing bearing resting in said base bearing and also having parallel horizontally spaced upwardly facing concave bearings, and a rocker having complementary downwardly facing bearings pivotally seated in said parallel seat bearings. 20
7. In a rocker bearing device, a seat, and a rocker having spaced pivots on said seat, said rocker and seat being adapted to rock as a unit transversely of the plane of rocking movement of said rocker on said pivots. 25
8. A rocker bearing comprising a load supporting member, a rocker having spaced pivots and adapted to carry said load supporting member, a rocker seat having spaced bearings for said pivots, said rocker and seat being adapted to rock as a unit transversely of the rocking movement of said rocker on said bearings. 30
9. In a rocker bearing, a base member for rigid application to a truck, a rocker seat mounted on said base member so as to pivot thereon in one plane, a rocker pivoted on said seat so as to tilt about a predetermined axis thereon in a plane extending transversely of said first mentioned plane, and an element resting on said rocker for rigid application to body structure to be carried by said truck. 45
10. In a rocker bearing, a base member for rigid application to a truck, a rocker seat having a single bearing on said base so as to pivot thereon in one plane, a rocker having spaced bearings on said seat so as to pivot thereon in a plane extending transversely of said first mentioned plane, and an element resting on said rocker for rigid application to body structure to be carried by said truck. 50
11. In a rocker bearing, a base member for rigid application to a truck, a rocker seat mounted on said base member so as to 55
- pivot thereon in one upright plane, a rocker pivoted about a predetermined axis on said seat so as to tilt thereon in an upright plane extending transversely of said first mentioned plane, an element resting on said rocker for rigid application to body structure to be carried by said truck, and interengaging parts on said rocker and element for maintaining desired relation between them. 60
12. In a rocker bearing, a base member for rigid application to a truck, a rocker seat mounted on said base member so as to pivot thereon in one upright plane, a rocker pivoted about a predetermined axis on said seat so as to tilt thereon in an upright plane extending transversely of said first mentioned plane, an element resting on said rocker for rigid application to body structure to be carried by said truck, and parts on said rocker and element for positively maintaining lateral interengagement thereof, irrespective of their pivotal movement on said base member. 65
13. In a rocker bearing, including a load supporting member, a rocker supporting said member and having spaced pivots on its lower portion and oppositely curved cam surfaces on its upper portion, and a rocker seat, said rocker and seat being adapted to rock transversely of the rocking movement of said rocker. 70
14. In a rocker bearing, a rocker having spaced pivots on its lower portion and oppositely curved cam surfaces on its upper portion, a rocker seat, said rocker and seat being adapted to rock transversely of the rocking movement of said rocker. 75
15. In a rocker bearing, a load supporting member having relatively inclined surfaces on its under side, a rocker supporting said member and having spaced pivots on its lower portion and oppositely curved cam surfaces on its upper portion, and a rocker seat, said rocker being interengaged with said load supporting member, and said rocker and seat being adapted to rock transversely of the rocking movement of said rocker. 80
16. In a rocker bearing, a load supporting member having double inclined surfaces on its under side and lugs depending therefrom, a rocker supporting said member and having spaced pivots on its lower portion, and oppositely curved cam surfaces on its upper portion, and a rocker seat, said rocker having recesses adapted to receive said lugs. 85
17. In a rocker bearing, a base member for rigid application to a truck, a rocker seat mounted on said base member so as to pivot thereon in one plane, a rocker pivoted on said seat so as to tilt about a predetermined axis thereon in a plane extending transversely of said first mentioned plane, an element resting on said rocker for rigid application to body structure to be carried 90
18. In a rocker bearing, a base member for rigid application to a truck, a rocker seat mounted on said base member so as to 95
- pivot thereon in one plane, a rocker pivoted about a predetermined axis on said seat so as to tilt thereon in an upright plane extending transversely of said first mentioned plane, an element resting on said rocker for rigid application to body structure to be carried 100
19. In a rocker bearing, a base member having relatively inclined surfaces on its under side, a rocker supporting said member and having spaced pivots on its lower portion and oppositely curved cam surfaces on its upper portion, and a rocker seat, said rocker being interengaged with said load supporting member, and said rocker and seat being adapted to rock transversely of the rocking movement of said rocker. 105
20. In a rocker bearing, a load supporting member having double inclined surfaces on its under side and lugs depending therefrom, a rocker supporting said member and having spaced pivots on its lower portion, and oppositely curved cam surfaces on its upper portion, and a rocker seat, said rocker having recesses adapted to receive said lugs. 110
21. In a rocker bearing, a base member for rigid application to a truck, a rocker seat mounted on said base member so as to pivot thereon in one plane, a rocker pivoted on said seat so as to tilt about a predetermined axis thereon in a plane extending transversely of said first mentioned plane, an element resting on said rocker for rigid application to body structure to be carried 115
22. In a rocker bearing, a base member having relatively inclined surfaces on its under side, a rocker supporting said member and having spaced pivots on its lower portion and oppositely curved cam surfaces on its upper portion, and a rocker seat, said rocker being interengaged with said load supporting member, and said rocker and seat being adapted to rock transversely of the rocking movement of said rocker. 120
23. In a rocker bearing, a base member having double inclined surfaces on its under side and lugs depending therefrom, a rocker supporting said member and having spaced pivots on its lower portion, and oppositely curved cam surfaces on its upper portion, and a rocker seat, said rocker having recesses adapted to receive said lugs. 125
24. In a rocker bearing, a base member for rigid application to a truck, a rocker seat mounted on said base member so as to pivot thereon in one plane, a rocker pivoted on said seat so as to tilt about a predetermined axis thereon in a plane extending transversely of said first mentioned plane, an element resting on said rocker for rigid application to body structure to be carried 130

by said truck, and interengaging parts on said rocker and element for maintaining the desired relation between them.

18. In a centering device for mounting a railway vehicle frame upon a truck so as to swing transversely of the truck, a base member with a concave upwardly-facing bearing, a seat having a complementary downwardly-facing bearing resting on said base bearing and also having an upwardly-facing concave bearing, and a rocker having a complementary downwardly-facing bearing pivotally seated in said upwardly-facing bearing of said seat.

19. In a centering device for mounting a railway vehicle frame upon a truck so as to swing transversely of the truck, a load supporting member, a rocker supporting said member and having spaced pivots on its lower portion and oppositely curved cam surfaces on its upper portion, and a rocker seat, said member, rocker and seat being arranged to rock transversely of the rocking movement of said rocker on said seat.

20. In a centering device for mounting a railway vehicle frame upon a truck so as to swing transversely of the truck, a rocker having spaced pivots on its lower portion and oppositely curved cam surfaces on its upper portion, and a rocker seat, said rocker and seat being arranged to rock transversely of the rocking movement of said rocker on said seat.

In testimony whereof I hereunto affix my signature this 12th day of February, 1926.

LILIAN A. WESTLAKE,
*Administratrix of the Estate of Charles T.
Westlake, Deceased.*
